CONTROL OF PRINTING MEANS

Oscar J. Sundstrand, Bridgeport, Conn., assignor
to Underwood Elliott Fisher Company, New
York, N. Y., a corporation of Delaware

Application December 30, 1933, Serial No. 704,695

18 Claims. (Cl. 101—93)

The invention relates to new and improved means to differentially control the movement of the type carrying elements of printing and/or computing machines.

More particularly it relates to simplified means to differentially control a plurality of character printing type bars.

It is an object of the present invention to increase the printing capacity of character or non-cumulative data of such machines without correspondingly increasing the number of character or non-cumulative data keys.

It is another object of the invention to multiply the capacity of the keyboard structure of machines of the above character.

Referring to the drawing.

Figure 1 is a fragmental elevational view of one embodiment of the invention.

Figure 2 is a fragmentary plan view of the structure shown in Figure 1.

Figure 3 is a detailed view of certain parts of the mechanisms.

Figure 4 is a fragmentary perspective view of certain parts of the structure shown in the Figures 1 and 2.

Figure 5 is a plan view of certain of the structure shown in Figure 1.

The present invention is herein embodied in a non-cumulative keyboard section of a computing and printing machine similar to that fully disclosed in my application Serial No. 581,800 filed December 18, 1931, to which application reference may be had for an understanding of features not fully shown in the present drawing. It should be understood, however, that the invention is not limited to such machines, nor, particularly, to the non-cumulative sections of keyboard structures but may be adapted to various other forms and arrangements of computing machines and to the amount keyboards thereof.

In the drawing, two type bars 10 and 11 are shown. These type bars are preferably of the same form and operatively supported in the same general way as is disclosed in my beforementioned application. Each type bar is provided adjacent its upper end with a plurality of superimposed types (not shown) arranged to make impressions upon a conventional paper carrying platen.

Forwardly extending arms 12 and 13 are pivoted adjacent the lower portions of the respective type bars, the arms in turn slidably supporting independent stop pins 15 and 16. The pins 15 and 16 are guided for vertical movement in a stationary guide bar 17 extending transversely of the machine.

The guide bar 17 is positioned rearwardly of a keyboard section including a bottom wall 18, side wall 19, end wall 20, and a top plate 21. A plurality of keys 22 fitted with similar stems 23 are guided for vertical movement in aligned slots 5 formed in the bottom wall 18 and top plate 21.

The stem 23 of each of the keys 22 is operatively connected to a slide 24 through the medium of similar bellcranks 25, pivotally supported in the side walls of the keyboard section. The rear ends 10 of each of the several slides 24 project through, and are supported by, the end wall 20, the remote end of each slide constituting in effect, a stop, the tines 26 and 27 of which are aligned with the pins 15 and 16. A locking slide 28, slidably supported 15 in underlying relationship with respect to the several key stems 23 is provided with similarly formed and equally spaced forwardly extending lugs 29, one such lug being associated with each key stem. It will be apparent from Figure 1 that depression of any one of the keys 22 will function to move the slide 28 forwardly and that the lug acted upon will operate to lock the actuated key in its lower or depressed position. The rear end of slide 28 projects through the end wall 20 to 25 define a stop 30 normally effective to restrain the pin 16, and hence the type bar 11 against upward movement.

Hence it will be apparent that depression of any one of the keys 22 will function to retract the stop 30 and thus permit the pin 16, and its associated type bar 11, to rise to a position predetermined by the height of the particular one of the slides 24, which was operated.

As shown in Figure 2, each of the keys 22 is 35 provided on its top surface with a plurality of characters, in the present instance, the letters X and Y being shown upon the lower-most one of the keys 22. It will be understood that each of the keys 22 intermediate those shown will be 40 similarly inscribed with a plurality of different symbols and that such symbols will preferably be arranged in a horizontal line as shown to more clearly establish a relationship between the several sets of symbols or characters employed. Depression of any one of the several keys 22 is effective to cause the type bar 11 to rise to a point identified with the printing of the left hand one of the characters shown.

Means is provided to effect the printing of the right hand one of any one of the characters appearing upon the keys 22.

To this end a key 31, structurally similar to the keys 22, and herein designated the auxiliary key, 55

- is operatively supported in the keyboard section. As shown in Figure 1, the stem 32 of key 31 is effective to operate a slide 33 through a medium of a bell crank 34 similar in the present instance, to the bell cranks 25. The rear end of slide 33 projects through the end wall 20, as shown in Figure 2, and comprises an irregularly shaped portion 35 effective to block the path of either one, but not both, of the pins 15 and 16.
- 10 When the key 31 is in its normal or elevated position, the part 35 overlies and thus blocks the pin 15, as shown in Figure 2, whereas when the key 31 is depressed a tine 36 on the part 35 moves rearwardly into blocking relation with respect to the pin 16, and a notch 37, adapted to permit free movement of the pin 15 therethrough, is aligned in the path of movement of the latter part. Thus it will be obvious that when any one of the keys 22 is depressed in combination with the key 31, the type bar 11 will be blocked against movement and the type bar 10 will be permitted to rise until its pin 15 is stopped by the tine 26, of the particular slide 24, which has been moved rearwardly by its key 22.
- 15 It will be apparent that in thus rising to the height predetermined by the position of the tine 26 above the normal rest position of the pin 15, that a type corresponding to the right hand figure of the key 22, which was depressed, will be positioned for printing. With a view to insuring certain differentiation between the respective characters on the several keys 22, that portion of the surface of the key which bears the inscription of the character printed as an incident to depression of the auxiliary character key is preferably distinctively colored to correspond with the coloring of the key 31.
- 20 To prevent the possibility of the type bar 10 rising to its upper-most position when the key 31 alone is depressed, the following means is employed: An arm 38 secured adjacent one of its ends to a lug 29 of the slide 28, projects through the end wall 20, to define a stop 39 effective to prevent any movement of the type bar except in those instances in which one of the keys 22 is additionally operated.
- 25 In operation of the invention, depression of any one of the keys 22, without an accompanying depression of key 31, will result in printing of the left hand or normal character associated with that key. As has been described, such an operation results in retraction of the stop 30 and positioning of the tine 27 on one of the slides 24 in the path of movement of the pin 16. Coincidentally with retraction of the stop 30, the arm 38 is retracted to displace the stop 39, but the type bar 10 will only be permitted to rise to the plane of the part 35 of slide 33 in which position the type bar 10 is not effective to print.
- 30 Depression of any one of the keys 22 in conjunction with the key 31 similarly functions to retract the stop 30, but the tine 36 of the part 35 is moved rearwardly to block the pin 16 and thus prevent effective movement of the type bar 11.
- 35 The before mentioned movement of part 35 is effective to position its notch 37 in alignment with the path of movement of pin 15 to thus permit the bar 10 to rise until its pin 15 is blocked by the tine 26 of the particular key 22 which was operated.
- 40 It will be seen that I have provided new and improved means effective to increase the capacity of the control of printing means by a given number of keys.
- 45 I claim as my invention:
- 70 1. A pair of type bars, a group of keys each

bearing a character associated with each of said type bars, said keys being individually operable to differentially position stops to control the extent of movement of either of said bars, a part normally effective to prevent movement of one of said bars, a part normally effective to prevent movement of the second of said bars, means operable by any one of said group keys to disable said first mentioned part to permit said one type bar to move, and a key effective to disable the second of said parts to permit said second bar to move and to block said one bar against movement.

2. A pair of type bars, a group of keys each bearing a character associated with each of said type bars, said keys being individually operable to differentially position stops to control the extent of movement of either of said bars, a part normally effective to prevent movement of one of said bars, a second part effective in one position to prevent movement of the second of said bars and in another position to prevent movement of said one bar, means operable by any one of said group keys, to disable said first mentioned part, and a key effective to move the other of said parts to position to permit said second bar to move and to block the one said bar against movement.

3. A pair of type bars, a group of keys individually operable to differentially position stops effective to determine the extent of movement of either of said bars, stop means effective to prevent movement of one of said bars, means actuated by any one of said group of keys to disable said stop means, a second stop movable from a position in which it prevents movement of the second of said bars to a position in which it is effective to prevent movement of the first one of said bars and a key arranged to actuate said second stop.

4. A pair of type bars, a plurality of keys individually operable to predetermine the extent of upward movement of either of said type bars, a member normally effective to prevent upward movement of one of said type bars and a key operable to disable the means normally tending to prevent movement of one of said type bars and to block movement of said other type bar.

5. A pair of normally disabled type bars, a group of keys individually operable to release, and differentially control, the extent of movement of one of said bars, and a single key operable in conjunction with any one of said group of keys to block said one bar against movement and to release the second bar for movement to an extent determined by the particular one of the group keys operated.

6. A group of normally disabled type bars, a group of keys individually operable to enable one of said bars and differentially control the extent of movement of either of said bars, and a key and connections to disable said one bar and permit movement of the second of said bars to an extent predetermined by one of said group of keys.

7. A pair of type bars; individual stops associated with each one of said bars, a key bearing characters associated with each of said bars, said key being operable to disable the stop associated with one of said bars and to position a part in the path of said bar corresponding to the printing position of one of said characters; a second key operable to disable the stop associated with the second of said bars and to position a part effective to prevent movement of the first of said bars, said keys being jointly operable to prevent movement of said first mentioned bar and to

permit movement of said second bar to a position to print a character corresponding with the second of the characters on said first mentioned key.

5 8. A plurality of type bars, a group of keys individually operable to differentially control movement of one of said type bars and another key operable in conjunction with any one of said group of keys to prevent movement of said one type bar and differentially control the movement of another of said type bars.

10 9. A group of normally disabled type bars, a group of keys individually operable to enable one of said bars and to differentially control the extent of movement thereof, and a single key to disable said first mentioned bar and enable movement of a second bar.

15 10. A pair of normally disabled type bars, a key operable to predetermine the extent to which either one of said pair of type bars shall move, and a second key operable to release the second one of said bars for movement and to disable the other of said bars.

20 11. A pair of type bars, a group of keys individually operable to predetermine the extent of movement of either of said bars, and a single key operable in conjunction with one of said group of keys to predetermine which of said pair of bars shall be released for movement.

25 12. A pair of normally disabled type bars, a key operable to release one of said bars for movement and to predetermine the extent of movement of either of said bars, and a second key operable to prevent movement of said first men-

tioned bar and to enable movement of the second bar.

30 13. In a machine of the class described, the combination of a plurality of differentially movable type bars, and a single bank of keys common to said group of type bars and operable singly, and in combination one with another, to predetermine the particular one of the bars which shall move and the extent of such movement.

14. In a machine of the class described, the combination of two differentially movable type bars, a single set of keys associated with said bars to predetermine the extent of movement thereof, and means for selecting a single bar for movement.

15 15. A group of differentially movable type bars, a single group of keys operable to predetermine the extent of movement of either of said bars and means to predetermine which of said bars shall move.

20 16. A pair of type bars, a group of keys operable to predetermine the extent of movement of either of said bars, and a key to disable one bar and enable another.

25 17. A pair of type bars, a key operable to predetermine the extent of movement of either of said bars, and a second key to determine which of said bars shall move.

30 18. A pair of type bars differentially movable corresponding distances to present different characters, a group of keys effective to predetermine the extent of such movement, and another key to determine which of said bars shall move.

OSCAR J. SUNDSTRAND.
